United States Patent Office

Des. 210,722
Patented Apr. 9, 1968

210,722

INCINERATOR

Harry S. McDowell, Cuyahoga County, Ohio, assignor to The Donley Brothers Company, Cleveland, Ohio, a corporation of Ohio

Filed June 7, 1967, Ser. No. 7,387

Term of patent 14 years

(Cl. D23—85)

The broken line showing of flue structure is for illustrative purposes only.

I claim:

The ornamental design for an incinerator, as shown and described.
